UNITED STATES PATENT OFFICE.

NELSON SANFORD STEWART, OF AMSTERDAM, NEW YORK, ASSIGNOR TO STEPHEN SANFORD & SONS, OF SAME PLACE.

DESIGN FOR CARPETING.

SPECIFICATION forming part of Design No. 31,168, dated July 4, 1899.

Application filed February 17, 1899. Serial No. 705,903. Term of patent 3½ years.

To all whom it may concern:

Be it known that I, NELSON SANFORD STEWART, a citizen of the United States, residing at Amsterdam, in the county of Montgomery and State of New York, have invented and produced a new and original Design to be Worked into or upon Carpeting or Similar Fabrics; and I do hereby declare that the drawing accompanying this specification gives and conveys to any one skilled in the art of carpet-weaving a clear understanding of the same that is sufficient to enable such persons to use my invention.

The said drawing is a face view of the carpet embodying my design, consisting of scrolls in the renaissance style and also leaves and flowers, all arranged and treated as shown in the said drawing.

What I claim, and desire to secure by Letters Patent, is—

The design for carpeting substantially as shown and described.

In testimony whereof I have signed my name to this specification in the presence of two subscribing witnesses.

NELSON SANFORD STEWART. [U. S.]
